Jun. 5, 2019 (JP) 2019-12338

The ornamental design for an automotive charging connector cap, as shown and described.

(51) **LOC (13) Cl.** **13-03**

DESCRIPTION

(52) **U.S. Cl.**

FIG. 1 is a front, top and right side perspective view of an automotive charging connector cap showing my new design;

USPC **D13/120**

FIG. 2 is a front view thereof;

(58) **Field of Classification Search**

FIG. 3 is a top plan thereof;

USPC D8/395; D13/102–106, 110, 119–121,

D13/156, 184, 199; D12/197

CPC H01R 11/24; H01R 11/281; H01R 11/282;

H01R 11/286

FIG. 4 is a bottom plan thereof;

See application file for complete search history.

FIG. 5 is a right side thereof;

(56) **References Cited**

FIG. 6 is a left side view thereof;

U.S. PATENT DOCUMENTS

FIG. 7 is an enlarged cross-sectional view taken along line 7-7 in FIG. 2;

D227,989 S * 7/1973 Gelsel D13/156

FIG. 8 is an enlarged bottom view showing the state in

D602,433 S * 10/2009 Katou D13/120

which a strap is removed;

D629,366 S * 12/2010 Ericson D13/156

FIG. 9 is an enlarged left side view showing the state in

D765,606 S * 9/2016 Hack D13/156

which a strap is removed; and,

D864,067 S * 10/2019 Kito D12/197

FIG. 10 is an exploded perspective view thereof.

D864,825 S * 10/2019 Kito D12/197

The broken lines illustrate portions of the automotive charging connector cap that form no part of the claimed design.

D864,826 S * 10/2019 Kito D12/197
